UNITED STATES PATENT OFFICE

RALPH Z. HOPKINS AND EARL F. SEGER, OF DETROIT, MICHIGAN, ASSIGNEES TO
HUDSON MOTOR CAR COMPANY, OF DETROIT, MICHIGAN, A CORPORATION OF
MICHIGAN

STRIPING DEVICE FOR AUTOMOBILE BODIES

Application filed July 2, 1928. Serial No. 289,811.

This invention relates to striping devices particularly adapted for the purpose of striping automobile bodies, such as along or adjacent the belt line molding or around the 5 window reveals.

An object of the invention is to provide an improved portable striping device which will be relatively simple and compact in construction and efficient in use, and in which 10 the device may be easily handled and guided over the body so as to permit its use by unskilled labor, whereby the work of striping may be rapidly and cheaply done.

A further object of the invention is to provide 15 a striping device having improved means for feeding the paint or striping fluid to the applicator or pen, so that the proper amount of paint will be supplied along the line of striping irrespective of the speed at which the device is moved over the body. Moreover it is one of the purposes of the invention to provide a striping device so constructed as to produce a better and more 20 clearly defined stripe, in which the paint or fluid may be controlled at the applicator point, so that not only will the strip have more body or depth but also the danger of 25 ragged or uneven edges will be prevented.

Other objects of the invention will appear 30 in the following description and appended claims, reference being had to the accompanying drawings forming a part in this specification wherein like reference characters designate corresponding parts in the several views.

Fig. 1 is a perspective view illustrating a 35 device embodying the invention in position for producing a stripe on the belt line molding of a body panel.

Fig. 2 is a central sectional elevation of the 40 construction shown in Fig. 1.

Fig. 3 is a sectional plan view illustrating 45 particularly the guiding means for the device.

Fig. 4 is a fragmentary perspective view, 50 partly in section, illustrating the upper part of the device including the applicator.

Fig. 5 is a perspective view illustrating 55 another embodiment of the invention in use for

applying a stripe along a belt line molding of a body panel.

Fig. 6 is a central sectional elevation of the 55 construction shown in Fig. 5.

Fig. 7 is a sectional view taken substantially 60 on lines 7-7 of Fig. 6.

Fig. 8 is a detail sectional view illustrating 65 the guiding means for the device of this embodiment.

Before explaining in detail the present invention, it is to be understood that the invention is not limited in its application to the details of construction and arrangement of parts illustrated in the accompanying drawings, 70 since the invention is capable of other embodiments and of being practiced or carried out in various ways. Also it is to be understood that the phraseology or terminology employed herein is for the purpose of description and not of limitation, and it is not intended to limit the invention beyond 75 the terms of the several claims hereto appended as considered in view of the prior art and the requirements thereof.

Referring to Figs. 1 to 4 inclusive the 80 striping device in this form of the invention comprises a hollow supporting body forming a reservoir 10 for containing the striping fluid or paint. This reservoir or container body is constructed to provide an inner straight wall 10a and an outer offset wall 10b, and the upper end of the container body is screw threaded for the attachment of a screw cap 11. Extending through the interior of 85 the reservoir or container 10 is a tube 12, this tube extending parallel to the wall 10a and closely adjacent thereto. The lower end of the container body 10 is reduced and formed with a cylindrical extension 13 within which is fixed the lower end of the tube 12. The 90 tube 12 preferably extends to a point adjacent the top of the container body and in the present instance is open at 14 providing a port normally located above the highest level 95 of the fluid or paint within the reservoir, thereby providing a return for excess paint as will be later described. The tube 12 at its lower end is also provided with a port 15 permitting the feed of paint or fluid into the 100 tube from the reservoir.

Within the tube 12 is located a screw or worm conveyor 16, which preferably extends substantially the length of the tube 12 and terminates at a point adjacent the upper end 5 thereof near the port 14. The lower end 17 of this screw or worm 16 is cylindrical and is machined to provide an annular key 17a housed within an undercut annular groove in a bearing cap 19. This cap is tapped and is 10 adapted to be screwed onto the threaded end 18 of the extension 13. In this manner the screw conveyor 16 has a bearing within the cap 19 and is supported thereby to rotate within the tube 12. The end of this shaft is 15 also turned down to provide a projecting spindle 20 upon which is fixed a roller 21. This roller is preferably composed of yieldable frictional material, such as rubber, so that when it is held against the body panel 20 and when the device is moved along the body the rotation of the roller will result in driving the conveyor 16.

Intermediate the ends of the tube 12, and 25 preferably adjacent the upper end of the container body 10, the latter is provided with an applicator 22. In the present instance this applicator comprises a hollow arm extending from the container. The arm 22 is substantially square in cross section, and extending 30 therethrough is a tube or duct 23 communicating with the interior of the feed tube 12. The outer end of the arm 22 forms the applicator tip 22a by which the paint or fluid is applied to the body to form the stripe. This 35 applicator tip or surface is preferably concave or curved as shown in Fig. 4, and is provided with a series of parallel alternate grooves and ribs 25 which extend in the direction in which the stripe is formed. The 40 applicator tip in this instance is therefore concave and fluted and the tube 23 communicates with this surface by means of a port 24 preferably entering one of the grooves which is more remote from the reservoir 10. The 45 purpose of the grooves 25 is to form small channels for holding the fluid at the applicator tip, the ribs being curved so that when the device is moved over the body the paint will spread over the entire surface of the applicator tip, while at the same time preventing the paint from spreading so as to provide 50 ragged marginal edges. Thus when the applicator is moved over the body, and especially over a curved surface such as the belt line molding 51, the paint will be partially separated and held within the series of small channels or grooves 25. Where the concave end or tip of the applicator has the same contour as the molding 51 all of the ribs 25a 55 will engage the face of the molding, and in effect the stripe when formed will be a series of very close lines, but due to the fluidity of the paint these lines will immediately merge producing a single stripe. As a result 60 of this construction a relatively wider stripe

may be produced, while at the same time maintaining a straight even marginal edge.

The guide structure for the striping device in this instance comprises a pair of bars or socket members 26 straddling opposite sides 70 of the container body 10 and secured thereto, as by soldering. Each of these bars is provided with a square hole within which slidably extends a guide bar 27 which is connected to the socket member 26 by means of a pin and slot connection 31. The inner ends of the bars 27 act against compression springs 30, and the outer ends of these bars are connected by means of a curved or arched 75 rod or wire 28 carrying a curved guide tip 29. The guide tip 29 is adapted to engage along a projection on the body during the striping operation, such as along the belt line molding 51, as shown in Fig. 1, and the guide is yieldable against the action of the springs 30 so that the applicator will travel along the surface and produce a stripe only by applying pressure so as to cause the guide to yield and permit engagement of the applicator 80 with the surface to be striped.

Referring to the embodiment shown in Figs. 5 to 7 inclusive the construction of the container body or reservoir, and the force feed mechanism is substantially the same as above described, with the exception that in this instance a conical roller 35 is provided instead of the circular or ball-shaped roller 21.

In this construction a pen 36 is provided which is mounted at the upper end of a supporting bar 37, which is preferably square or rectangular in cross section. The bar 37 is supported at one side of the container body 10, at its lower end by a rod 38 fixed to the lower end of the body and its upper end may be soldered or otherwise secured to the container. The pen 36 comprises a stationary nib 39 and a hinged nib 39a, these nibs being connected together and adjustable toward 10 and from each other by means of a set screw 40. The paint or striping fluid is fed to the pen nibs by means of a tube or duct 55, the outer end thereof terminating a suitable distance in rear of the pen points, and the inner end fitting into a hole in the tube 12 intermediate the openings 14 and 15.

Below the pen 36 there is mounted on the supporting bar 37 a guiding device for the striping. Slidable upon the bar 37 is a sleeve 41 held in adjusted position by means of a set screw 42. Secured to the outer side of this sleeve is a second sleeve 43 extending transversely thereto and having a square opening therethrough. Extending through this opening is a socket member 44 which is slidable therein and held in adjusted position by means of a set screw 45 extending through a slot 46 in the sleeve 43. The socket member 44 has a square hole into which extends a guide bar 47 acted upon by a spring 125

48. This bar is connected to the member 44 by means of a pin and slot connection 49, and the end of the guide bar is provided with a ring tip 50 adapted to engage a projection on the surface to be striped, such as the belt line molding 51.

The device shown in Figs. 1 to 4 inclusive is illustrated as being employed for applying a strip 61 on the rib or belt line moulding 51 of an automobile body, a portion of one of the body panels being shown at 60. The device is grasped by the operator and held in position against the body so that the guide tip 29 will engage one edge of the molding 51, with the roller 21 in contact with the face of the panel 60. In the illustrated device the construction is such that the applicator 22 extends in a position to cause the concave striping tip 22a thereof to engage the convex face of the molding 51 upon exerting a slight pressure to cause the guide 27-29 to yield against the action of the spring 30. As the device is moved over the body the friction member 21 will rotate, thereby driving the conveyor screw 16, and forcing the fluid through the duct or tube 23. The feed of the paint fluid will be proportionate to the speed in which the device is moved over the body, since this governs the speed of rotation of the roller 21 and the screw 16. Any excess paint which is not taken up by the tube 23 and forced through the port 24 will be returned to the reservoir through the opening 14 at the top of the feed tube 12.

35 In the construction illustrated in Figs. 5 to 8 inclusive a pen 36 is employed preferably when a narrower stripe is applied adjacent or along the belt line molding 51. The guiding mechanism in this instance is so constructed that the line of striping may be adjusted with relation to the rib or molding 51, and the guide is obliquely adjustable to permit striping on curved panels. It will be understood that where the device of Figs. 1 to 4 inclusive is to be used for striping along different lines with relation to the rib or molding 51, the guide structure of Fig. 5 may be employed instead of the guide structure shown in Fig. 1, thereby permitting the position of the line of striping to be adjusted.

What we claim is:

1. A striping device comprising a reservoir for a striping fluid, a tube within said reservoir having an opening above the level of fluid in the reservoir and also having an opening for conducting fluid into the tube, a feed screw within said tube, and an applicator communicating with said tube, said applicator having a duct located intermediate said openings.

2. A striping device comprising a reservoir for a striping fluid, a tube within said reservoir having an opening above the level of fluid in the reservoir and also having an opening for conducting fluid into the tube, a

feed screw within said tube, an applicator communicating with said tube, said applicator having a duct located intermediate said openings, and means for operating said feed screw.

70

3. A striping device comprising a reservoir for a striping fluid, a tube within said reservoir having an opening above the level of fluid in the reservoir and also having an opening for conducting fluid into the tube, a feed screw within said tube, an applicator communicating with said tube, and means connected to said screw and engageable with the surface to be striped for operating the screw.

75

4. A striping device comprising a reservoir for a striping fluid, a feed screw within said reservoir, a tube for said screw having an opening for conducting fluid into the tube and an opening for conducting fluid into the reservoir, an applicator communicating with the interior of said tube between said openings, and means for operating said screw and comprising a friction roller adapted to travel on a surface adjacent the line of striping.

80

5. A striping device comprising a reservoir for a striping fluid, a feed screw within said reservoir, a tube for said screw positioned within the reservoir and having an opening for conducting fluid into the tube and an opening for conducting fluid into the reservoir, an applicator communicating with the interior of said tube at a point located between said openings, yielding means for guiding said device, and means for operating said screw.

85

6. In a striping device, a receptacle having an inner straight wall and an outer offset wall forming a reservoir therebetween for striping fluid, a tube extending adjacent and parallel to said inner wall within the reservoir, said tube having a port adjacent its lower end for the flow of fluid into the tube and a port at its upper end for the return flow of fluid into the reservoir, an applicator communicating with the tube intermediate said ports, and means within said tube for forcing fluid to said applicator.

90

7. In a striping device, a receptacle having an inner straight wall and an outer offset wall forming a reservoir therebetween for striping fluid, a tube extending adjacent and parallel to said inner wall within the reservoir, said tube having a port adjacent its lower end for the flow of fluid into the tube and a port at its upper end for the return flow of fluid into the reservoir, an applicator communicating with the tube intermediate said ports, and a screw conveyor within said tube for forcing fluid to said applicator.

105

8. In a striping device, a receptacle forming a reservoir for striping fluid, a tube extending within the reservoir, said tube having a port adjacent its lower end for the flow

110

115

120

125

130

of fluid into the tube and a port at its upper end for the return flow of fluid into the reservoir, an applicator communicating with the tube intermediate said ports, resilient means for holding said applicator in predetermined position relative to the striping surface, and means within said tube for forcing fluid to the applicator.

9. In a striping device, a receptacle having enclosing walls forming a reservoir for striping fluid, a tube extending parallel to an inner wall within the reservoir, said tube having a port adjacent its lower end for the flow of fluid into the tube and a port at its upper end for the return flow of fluid into the reservoir, an applicator communicating with the tube intermediate said ports, a feed screw extending through said tube beyond said last port, and a rotary member engageable with an exterior surface for driving said screw.

10. In a striping device, a reservoir for striping fluid, an applicator, a rigid feed screw within said reservoir, a tube enclosing said screw and having a port for the flow of fluid into the tube, said applicator communicating with said tube at a point located intermediate the ends of the tube, and a roller adapted to travel on an exterior surface for operating said screw to feed fluid to the applicator.

11. In a striping device, an applicator having a concave corrugated striping surface, and a port opening into said surface for feeding the fluid thereto.

12. In a striping device, a reservoir for striping fluid, an applicator having a corrugated striping surface providing a series of parallel grooves, and a feed conduit leading from said reservoir and opening into said corrugated surface.

13. In a striping device, an applicator having a corrugated striping surface and provided with a port extending through said surface for feeding fluid thereto.

In testimony whereof we affix our signatures.

RALPH Z. HOPKINS.
EARL F. SEGER.
